UNITED STATES PATENT OFFICE.

FLOYD B. O'BRIEN, OF CHICAGO, ILLINOIS.

DESIGN FOR A VANITY CASE.

Application filed May 11, 1922. Serial No. 2,179. Term of patent 3½ years.

To all whom it may concern:

Be it known that I, FLOYD B. O'BRIEN, a citizen of the United States, residing at Chicago, in the county of Cook and State of Illinois, have invented a new, original, and ornamental Design for a Vanity Case, of which the following is a specification, reference being had to the accompanying drawing, forming part thereof.

Fig. 1 is a side elevational view of a vanity case showing my new design and

Fig. 2 is an end elevational view of the same.

I claim:

The ornamental design for a vanity case substantially as shown.

FLOYD B. O'BRIEN.
